US00D884738S

(12) United States Design Patent (10) Patent No.: US D884,738 S
Sepulveda (45) Date of Patent: * May 19, 2020

(54) DISPLAY SCREEN OR PORTION THEREOF
WITH ICON

(71) Applicant: Apple Inc., Cupertino, CA (US)

(72) Inventor: Raymond Sepulveda, San Jose, CA (US)

(73) Assignee: Apple Inc., Cupertino, CA (US)

() Term: 15 Years

(21) Appl. No.: 29/672,879

(22) Filed: Dec. 10, 2018

Related U.S. Application Data

(60) Continuation of application No. 29/626,800, filed on Nov. 20, 2017, now Pat. No. Des. 835,673, which is a continuation of application No. 29/569,936, filed on Jul. 1, 2016, now Pat. No. Des. 803,263, which is a continuation of application No. 29/459,074, filed on Jun. 25, 2013, now Pat. No. Des. 760,762, which is a division of application No. 29/364,038, filed on Jun. 17, 2010, now Pat. No. Des. 684,987, which is a division of application No. 29/324,935, filed on Sep. 23, 2008, now Pat. No. Des. 618,248.

CLAIM

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,
FIG. 2 is another embodiment thereof.

The broken lines in the figures show a display screen or portion thereof, and form no part of the claimed design.

1 Claim, 1 Drawing Sheet
(1 of 1 Drawing Sheet(s) Filed in Color)

FIG. 1

FIG. 2
